United States Patent Office.

CHARLES W. A. ROMER, OF NEWARK, NEW JERSEY.

Letters Patent No. 96,968, dated November 16, 1869.

IMPROVEMENT IN HASP-LOCKS.

The Schedule referred to in these Letters Patent and making part of the same.

To all whom it may concern:-

Be it known that I, CHARLES W. A. ROMER, of Newark, in the county of Essex, and State of New Jersey, have invented a new and useful Improvement in Hasp-locks; and I do hereby declare the following to be a full, clear, and exact description thereof, which will enable those skilled in the art to make and use the same, reference being had to the accompanying drawing, forming part of this specification, in which drawing—

Figure 1 represents a longitudinal section of this invention.

Figure 2 is a front view of the locking-mechanism when the latch is locked.

Figure 3 is a similar view of the same, when the latch is thrown open and the bolt pushed back.

Similar letters of reference indicate corresponding parts.

This invention relates to certain improvements in that class of locks which serves to secure a hasp, provision being also made for sealing the lock, so that it cannot be opened without violating the seal.

The hasp is made to catch over a lug, which projects from an extension of the lock-plate, the latch being provided with a cavity in its under surface, which drops over said projection, and serves to increase the security of the mechanism.

The latch is locked by a bolt, which is driven outward by a spring, and retained by a series of tumblers.

As the latch is pressed down, its nose acts on a lever, which adjusts the tumblers before said nose strikes the head of the bolt, so that by the pressure on the latch, the bolt can be forced back, and made self-locking.

A safety-shield, applied between the key-hole and that portion of the tumblers which is acted on by the adjusting-lever, protects said portion against any instrument which might be introduced through the key-hole.

The latch is provided with a perforated lug, which, when said latch is locked, corresponds with a similar lug projecting from the key-hole guard, so that by passing a seal through these lugs, the key-hole as well as the latch are both sealed.

In the drawing—

The letter A represents the case, which encloses the locking-mechanism.

This case is provided with an extension, B, to which is hinged the latch C, and which is provided with a lug, a, to catch in the mortise of the hasp D, so that when the latch is closed down, said hasp is firmly retained.

In the under surface of the latch C is a cavity, b, to admit the top part of the lug a when the latch is

closed, so that the introduction of wedges is rendered difficult, and the security of the lock is materially increased.

The locking-mechanism consists of a bolt, E, which is driven forward by a spring, e, and retained in its forward position by tumblers d, as shown in fig. 2.

In order to be able to force the bolt back, the tumblers have to be adjusted. This object is effected by the action of the nose e of the latch on a lever, f, which is so formed that its tip projects somewhat beyond the head of the bolt, while its tail bears against the edges of the tumblers, a portion of which is so formed, that by the action of the lever f, the tumblers will be adjusted in position, to allow the bolt to recede.

As the latch is pressed down, therefore, the tumblers are adjusted by the action of the lever f, before the nose e strikes the head of the bolt, so that by the pressure of said nose, the bolt can be forced back.

After the edge of the nose e has passed the bolt, said bolt flies out, and retains the latch, and the tumblers reassume the position shown in fig. 2, the tip of the lever f being received by a cavity, g, (see fig. 1,) in the side of the nose e.

Between the key-hole and the tail of the lever f is a safety-shield, h, which prevents the introduction of an instrument, for the purpose of acting on those portions of the tumblers which are acted on by the lever f, and which are so formed that the tumblers could be readily adjusted by the action of any flat instrument.

The key-hole is protected by a spring-guard, i, which is provided with a perforated lug, j, to correspond to a similar perforated lug, k, projecting from the latch when said latch is closed.

By securing a seal in the lugs j k, both the latch and the key-hole guard are secured in position simultaneously, and neither the lock nor the hasp D can be opened without violating the seal.

What I claim as new, and desire to secure by Letters Patent, is—

1. The adjusting-lever f, in combination with the nose of the latch C, and with the tumblers d and bolt E, constructed and operating substantially as described.

2. The cavity g, in the side of the nose e of the latch, to operate in combination with the lever f and tumblers d, substantially as set forth.

3. The safety-shield h, in combination with the adjusting-lever f and tumblers d, as described.

This specification signed by me, this 25th day of August, 1869.

CHAS. W. A. ROMER.
